COMBINED MODULAR HOUSE TRAILER BODY AND PLATFORM

George Charles Innes, 508 Stafford Drive,
Elyria, Ohio 44035

Filed Aug. 9, 1971, Ser. No. 173,742

Term of patent 14 years

Int. Cl. D12—10

U.S. Cl. D12—103

FIG. 1

FIG. 2

FIG. 3

FIG. 4

FIG. 5

FIG. 1 is a right side elevational view of a combined modular house trailer body and platform showing my new design;

FIG. 2 is a top plan view thereof;

FIG. 3 is a rear end elevational view thereof;

FIG. 4 is a right rear perspective view thereof to a reduced scale; and

FIG. 5 is a top right rear perspective view thereof to a reduced scale.

The broken lines in the drawing are for illustrative purposes only.

The undisclosed left side is devoid of any doors or windows and consists of vertical siding, such as that shown in the right side, which continues throughout the entire left side. The undisclosed front end is identical to the rear end as shown.

I claim:

The ornamental design for a combined modular house trailer body and platform, as shown and described.
